THREAD CUTTER FOR PNEUMATIC THREAD RECEIVERS FOR LOOMS

Richard G. Turner, Worcester, Mass., assignor to
 Crompton & Knowles Loom Works, Worcester,
 Mass., a corporation of Massachusetts

Application October 25, 1947, Serial No. 782,133

14 Claims. (Cl. 139—247)

1

This invention relates to improvements in thread collectors of pneumatic thread control systems for the weft ends of reserve bobbins in weft replenishing looms and it is the general object of the invention to provide the collector with means for cutting off excess length of the weft ends.

Weft replenishing looms ordinarily operate with reserve bobbins in a magazine from which weft ends extend. It is necessary to keep these weft ends taut and also provide for their removal as the bobbins are transferred one by one during successive replenishing operations of the loom. Heretofore I have proposed control means for tensioning and removing weft ends including a thread collector or accumulator into which weft ends can be drawn pneumatically. After entering a thread holder associated with the collector the weft ends become entangled with each other to form a common mass of threads which serve as an anchorage to prevent the weft ends from being drawn out of the collector and back through the holder. I have also provided the thread collector with a door or the like affording manual access to the interior of the collector to permit the operator to remove excess weft ends.

It is an important object of the present invention to facilitate removal of the weft ends from the collector by providing the latter with cutter means to sever the weft ends, thereby avoiding the previous necessity of manually breaking off the end of a bundle or mass of threads which was necessary in thread collectors as heretofore constructed.

It is occasionally necessary for the weaver to place his hand into the thread collector to straighten out or otherwise manipulate the weft ends entering the collector from the thread holder, and under these conditions it is desirable that he be protected from accidental cutting by the cutter means. It is a further object of the present invention to mount the cutter so that it is normally unexposed and can be moved to exposed cutting position only at the weaver's will.

The form of thread collector with which the invention is illustrated utilizes a vertical hollow cylinder having a thread holder on the top thereof and means in the bottom thereof through which subatmospheric pressures may be created within the cylinder. In a collector of this type the weft ends are drawn down not only by gravity but also by pneumatic action, and it is a further object of the invention to locate the thread cutter at one side of the bundle or group of weft ends which hang from the thread holder intermediate

2

the latter and the means through which a partial vacuum is created within the receiver.

The cylindrical collector already mentioned has attached thereto a casing or the like which mounts a normally closed door which can be opened for reasons already mentioned herein. It is another object of the invention to locate the thread cutter adjacent to the door and in such position that it can sever weft ends after they have been drawn outwardly through the door.

Since it is desirable that the cutting operation shall leave some of the weft ends entangled with each other so that they can act as a thread anchorage it is still another object of the invention to locate the cutter at a substantial distance from the thread holder or point of entry of the weft ends into the collector.

With these and other objects in view which will appear as the description proceeds, my invention resides in the combination and arrangement of parts hereinafter described and set forth.

In the accompanying drawings, wherein a convenient embodiment of my invention is set forth, Fig. 1 is a side elevation of a thread collector made according to my present invention,

Fig. 2 is an elevation taken in the direction of arrow 2, Fig. 1, looking directly at the supporting casing for the door, the latter being removed,

Fig. 3 is a plan view looking in the direction of arrow 3, Fig. 2, parts being in section and parts being removed to illustrate more clearly the means for moving the cutter blade to cutting position,

Fig. 4 is a view of the door supporting casing and cutter as seen from the interior of the thread collector and looking in the direction of arrow 4, Fig. 3, and

Fig. 5 is an enlarged vertical section on line 5—5 of Fig. 3.

Referring particularly to Fig. 1, the thread collector or receiver R comprises a preferably transparent thin cylinder C having a base 10 held to a head 11 by tie bolts one of which is shown at 12. A thread holder H is supported by the head 11 and receives the weft ends W leading from the reserve bobbins in a magazine not shown. These weft ends are drawn pneumatically into the thread holder H and then downwardly into the cylinder C due to subatmospheric pressures created within the collector, through a porous tube 13 located in the bottom of the cylinder. Tube 13 communicates pneumatically with a hose 14 which may lead to any suitable source of subatmospheric pressures not shown, such as the reciprocating pumps which have already been pro-

posed by me. The head 11 may be supported on an arm 15 secured to and extending from the adjacent loomside not shown.

The cylinder has secured thereto a casing 16 having an outer flange 17 which is secured as at 18 to the cylinder. The casing has right and left side walls 20 and 21 as viewed in Fig. 4, a top 22, and a floor or bottom 23. The walls 20 and 21 are preferably inclined downwardly and away from the cylinder to engage a door D hinged as at 24 to the top of the casing 16. The top, bottom and side walls of the casing define a passageway 25 through which the weaver can insert his hand into the cylinder C and upwardly toward the thread holder H if it should be necessary to straighten out or otherwise manipulate the weft ends W. The latter will ordinarily hang downwardly from the thread holder as a mass M of entangled threads.

The matter thus far described may be as already proposed by me and operates in the usual manner. Subatmospheric pressures within the cylinder C draw weft ends into the holder and downwardly opposite passageway 25 toward porous tube 13. As new bobbins are placed in the magazine their weft ends will be drawn into the holder and cylinder and will generally be sufficiently long to reach at least to the top of the porous tube 13. As weaving continues the weft ends accumulate within the collector to a sufficient extent to require their occasional removal. In the past this has been done by lifting the door D and tearing the lower end of the threads away from their upper ends. This operation is not convenient nor does it always leave the mass M of sufficient length to serve as anchorage to prevent retrograde movement of the weft ends through the thread holder when their respective bobbins are picked immediately after transfer.

In carrying the present invention into effect I form the casing 16 with a horizontal flange or web 30 which may in effect be a continuation of the top 22 and extend into the cylinder as suggested in Fig. 3. A cutter blade 31 above the web 30 has one end thereof pivoted to the latter as at 32 while the other end thereof is connected as at 33 to a link 34. As indicated in Figs. 3 and 5 the link 34 extends backwardly, downwardly, and then forwardly through a guide lug 35 formed integrally with the casing in one of the upper corners of the passageway 25. The link extends forwardly beyond the guide lug 35 and is provided with a removable head or button 36. In order that the cutter blade may be held normally in the forward protected or unexposed position shown in Fig. 3 I surround the link with a compression spring 37 located between the guide lug 35 and the button 36. As shown more particularly in Fig. 3 the cutter blade is provided with a cutting edge 40 which is set forwardly of the rear edge 41 of web 30 by a sufficient amount to prevent accidental engagement with the weaver's wrist should his hand be placed into the collector C.

In the normal operation of the collector and pneumatic system the knife will be in the guarded position shown in Fig. 3, but when it is desired to remove excess weft ends from the interior of the collector the door D will be raised and the weaver will grasp the lower end of the mass M depending from the holder H while the thread cutter is in retracted or non-cutting position. He will then push the button 36 rearwardly to move the cutting edge 40 to the exposed cutting position shown in dotted lines in Fig. 3, and while holding the cutter in this position will move the weft

ends back and forth across the edge 40 to cut the lower part of the mass M from the upper part thereof. When the cutting operation is completed he will release the button, whereupon the spring 37 will move the cutting blade 31 back to guarded or non-cutting position, and after removal of the severed threads the door D will fall back to its normal position by gravity.

Ordinarily the weft ends hang down at one side of the blade 31, and although turbulence of air within the collector may disturb them to some extent the guard which is formed by the edge 41 of the web 30 as viewed in Fig. 3 will keep them out of contact with the cutting edge 40. The latter will be kept in non-cutting position at all times except when the weaver of his own will pushes button 36 rearwardly. There is therefore no opportunity for him to be cut accidentally, nor can the cutter effect a cutting operation with respect to the weft ends except by an intentional movement of the blade 31 to cutting position.

It is desirable that the cutter blade be located a substantial distance below the thread holder H, and while this distance may vary with different types of yarn, it will be desirable in any instance to have the cutter low enough so that such threads as remain above it will be long enough to form a substantial mass of entangled weft ends able to serve as a thread anchorage. The cutter and the means for operating it are located within the space subjected to subatmospheric pressures, and for this reason there is no air leakage into the pneumatic system because of the cutter. While this is a feature of practical consequence, I do not wish necessarily to be limited to a cutter which is located entirely within the cylinder or passageway 25.

From the foregoing it will be seen that I have provided a simple form of thread cutter mounted within the collector of a pneumatic thread control system for weft replenishing looms so located that it cannot normally cut either the weft ends or the weaver's hand. It will be seen that this result is accomplished by having a guard, which may conveniently be formed as a part of the casing 16, project rearwardly beyond the normal position of the cutting edge 40 maintained by spring 37. To this extent the web 30 may be considered a guard member and the blade 31 a cutter member, these members being movable relatively to each other at the will of the weaver to expose the cutter so that it can be engaged by the weft ends. It will further be seen that the cutter is located below the thread holder a substantial distance so that the uncut threads may serve as a thread anchorage. Also, the pneumatic action within the cylinder is such as to draw the threads normally along a path at one side of the cutter but near enough to it so that a cutting operation can be effected after the weft ends have been moved out through the passage 25.

Having thus described my invention it will be seen that changes and modifications may be made therein by those skilled in the art without departing from the spirit and scope of the invention and I do not wish to be limited to the details herein disclosed, but what I claim is:

1. In a pneumatic thread control system for the weft ends of reserve bobbins in a weft replenishing loom, a hollow collector into which the weft ends are drawn by subatmospheric pressures which exist normally within the collector, a normally closed door on the collector which when open affords access to the interior of the collector and through which the weft ends can be drawn

manually, and cutter means supported by the collector adjacent to the door to cut the weft ends after the latter have been drawn through the door.

2. In a pneumatic thread control system for the weft ends of reserve bobbins in a weft replenishing loom, a hollow collector into which the weft ends are drawn by subatmospheric pressures existing within the collector, a normally closed door on the collector which when open affords access to the interior of the collector and through which the weft ends can be drawn manually, and cutter means within the collector to cut the weft ends after the latter have been drawn through the door.

3. In a pneumatic thread control system for the weft ends of reserve bobbins in a weft replenishing loom, a hollow collector into which the weft ends are drawn by subatmospheric pressures existing within the collector, a normally closed door on the collector which when open affords access to the interior of the collector and through which the weft ends can be drawn manually, cutter means movably mounted within the collector, guard means within the collector normally keeping the weft ends out of engagement with the cutter means, and manually operable means to move the cutter means into cutting position with respect to the weft ends when the latter are drawn through the door.

4. In a pneumatic thread control system for the weft ends of reserve bobbins in a weft replenishing loom, a hollow collector into which the weft ends are drawn by subatmospheric pressures existing within the collector, a normally closed door on the collector which when open affords access to the interior of the collector and through which the weft ends can be drawn manually, a cutter member within the collector, a guard member for the cutter member within the collector, one of said members being movable relatively to the other and the guard member normally keeping the cutter member out of cutting relation with respect to the weft ends, and manually operable means to effect relative movement of said members to permit cutting relation between the cutter member and the weft ends when the latter are drawn through the door.

5. In a thread control system for the weft ends of reserve bobbins in a weft replenishing loom, a hollow collector for the weft ends, a cutter member within the collector, a guard member for the cutter member within the collector, one of said members being movable relatively to the other and said member being normally so related that the guard member keeps the weft ends out of cutting relation with respect to the cutter member, and means to effect relative movement of said members to enable the weft ends to engage the cutting member.

6. In a pneumatic thread control system for the weft ends of reserve bobbins in a weft replenishing loom, a hollow collector into which the weft ends are drawn by subatmospheric pressures existing within the collector, a normally closed door on the collector which when open affords access to the interior of the collector and through which the weft ends can be drawn manually, cutter means within the collector normally in noncutting position relatively to the weft ends when the latter are drawn through the door, and means mounted on the collector capable of moving the cutter means into cutting position relatively to weft ends when the latter are drawn through the door.

7. In a thread control system for the weft ends of reserve bobbins in a weft replenishing loom, a hollow collector in which the weft ends hang by gravity, and cutter means within the collector at one side of the weft ends against which the latter can be moved laterally for a cutting operation.

8. In a pneumatic thread control system for the weft ends of reserve bobbins in a weft replenishing loom, a hollow collector in which the weft ends are drawn downwardly by pneumatic action, and cutter means within the collector at one side of the weft ends against which the weft ends can be moved by lateral motion for a cutting operation.

9. In a pneumatic thread control system for the weft ends of reserve bobbins in a weft replenishing loom, a hollow collector from the top of which the weft ends are drawn downwardly by pneumatic action, and cutter means within the collector below the top of the latter and at one side of the weft ends against which the latter can be moved by lateral motion for a cutting operation.

10. In a pneumatic thread control system for the weft ends of a weft replenishing loom, a hollow thread collector in which subatmospheric pressures exist, a pneumatic thread holder on the upper part of the collector from which the weft ends are drawn downwardly into the collector by pneumatic action, a normally closed door on the collector which when open affords manual access to the weft ends, and cutter means within the collector above the door against which the weft ends can be moved for a cutting operation when the lower ends of the weft ends are drawn out of the door.

11. A pneumatic thread control system for the weft ends of a weft replenishing loom, a hollow thread collector in which subatmospheric pressure exist, a pneumatic thread holder on the upper part of the collector from which the weft ends are drawn downwardly into the collector by pneumatic action, a normally closed door on the collector which when open affords manual access to the weft ends at the thread holder, a cutter member within the collector above the door and below the thread holder and located intermediate the door and the weft ends, a guard member for the cutter member, said members normally so related as to keep the cutter member out of cutting relation with respect to the weft ends and the operator's hand when inserted through the door for manipulation of the weft ends at the thread holder, and manually operable means to effect relative movement of the members to expose the cutter means for a cutting operation relatively to the weft ends when the latter are drawn through the door.

12. In a pneumatic thread control system for the weft ends of a weft replenishing loom, a hollow thread collector in which subatmospheric pressures exist, a pneumatic thread holder on the upper part of the collector from which the weft ends are drawn pneumatically into the collector, a normally closed door on the collector which when open affords manual access to the weft ends at the thread holder, a cutter member within the collector above the door located at one side of the weft ends, a guard member for the cutter member, said members normally so related as to keep the cutter member out of cutting relation with respect to the weft ends and the operator's hand when inserted through the door for manipulation of the weft ends at the thread holder, and manu-

ally operable means to effect relative movement of the members to expose the cutter means for a cutting operation relatively to the weft ends.

13. In a pneumatic thread control system for a group of weft ends in a weft replenishing loom, a hollow thread collector in which subatmospheric pressures exist, a pneumatic thread holder on the upper part of the collector from which the group of weft ends are drawn pneumatically into the collector in entangled relation, and cutter means to cut the lower part of the group of weft ends from the upper part thereof at a point below the thread holder.

14. In a pneumatic thread collector for the weft ends of reserve bobbins in a weft replenishing loom, a hollow cylindrical member, a pneumatic thread holder for the weft ends on the top of the

cylindrical member, porous means in the bottom of the cylinder through which subatmospheric pressures can be created within the cylindrical member to draw weft ends downwardly from the thread holder toward the bottom of the member, and thread cutter means within the member intermediate the thread holder and porous means.
